UNITED STATES PATENT OFFICE.

LESTER S. KUBIAC, OF YOUNGSTOWN, OHIO, ASSIGNOR TO THE PHOTOGENIC MACHINE COMPANY, OF YOUNGSTOWN, OHIO, A CORPORATION OF OHIO.

ELECTRIC-ARC LAMP.

Application filed November 26, 1927. Serial No. 235,808.

This invention relates to electric arc lamps, and more particularly to the multiple type of lamp, involving an underslung construction, and including certain of the basic principles shown in my application Serial No. 147,206, filed November 9, 1926, and allowed May 6, 1927, but involving various improvements suggested by test and experience, the primary improvements probably residing in 5 an arrangement of operating bars and levers so assembled that the travel of the carbons or electrodes will be materially reduced as compared with the travel of armature of the solenoid, the relative travel of these two 10 elements being readily adjustable to any predetermined proportions.

I have learned from experience and practice that the starting and stopping of the carbons (in other words, the separation and 20 closing of the carbons for the purpose of establishing and terminating the arc) may be more gently effected by communicating or transmitting the movement of the armature to the carbons through the medium of a lever 25 slidably and loosely connected, intermediate its ends, with the clutch bar, one end of this lever being connected with the armature and the other end having a fixed pivot.

I also retain in the combination the counter-weight 21 shown in my former application, but necessarily somewhat differently mounted.

A practical embodiment of my invention is shown in the accompanying drawings, in 35 which Fig. 1 is a front elevation; Fig. 2 is an end elevation with the casing shown in section, and disclosing one coil of the rheostat or resisting elements, disposed at the rear of the casing enclosing the arc lights; Fig. 3 is 40 a plan view, partially in section, on line 3—3 Fig. 1; Fig. 4 is a fragmentary view, showing in detail the general arrangement and assembly of the various parts and elements of the operating mechanism; Fig. 5 is 45 a fragmentary front view, similar in some respects to Fig. 1, but more in detail, and also showing the carbons separated instead of closed as in Fig. 1.

I house the mechanism of my invention in 50 what may be termed an open supporting frame, designated, generally, as F, and consisting of the top or cap plate 1, the bottom or base plate 2, the back wall 3, and the four upright corner posts 4—4, which tie the cap 55 and base plates 1 and 2 together.

Rigidly secured to the cap and base plates 1 and 2, and adjacent the rear edges thereof, are the two upright columns or posts 5—5.

Mounted upon these two columns, intermediate their ends, is the solenoid bracket 6, and 60 the solenoid 7 is securely held in inverted position between this bracket 6 and the cap plate 1 of the frame by means of the bolts 8—8.

Also, slidably mounted upon the columns 65 5—5, beneath the bracket 6, by means of the relatively long tubular guide bearings 9—9, is the bar 10, carrying the oppositely lateral extension 11—11. Fig. 3.

Secured to the lower face of the bar 10 are 70 the ordinary dash posts 12—12, and the dash pot pistons 13—13 are swingingly secured to the upper face of the base plate 2 of the frame.

Depending from each of the lateral extensions 11—11 is a bolt or pin 14 provided at its lower end with a head 15, and upon which is mounted a coil spring 16.

Slidably mounted upon bolts 14—14, and above the springs 16—16, is a flat bar 17, 80 secured to the bolts by the nuts 18—18.

This is the same construction as shown in Fig. 6 of my former application, but inversely mounted.

The lower end of the armature 19 is secured 85 to the upper face of the flat bar 17.

Also, depending from the center of the bar 10 is a slotted post 20, the purpose of which will appear later.

Rigidly secured to the cap and base plates 90 1 and 2 of the frame, and adjacent the front edges thereof, are the two upright columns or posts 21—21.

Rigidly mounted upon these two columns, substantially on a level with the solenoid 95 bracket 6 on the columns 5—5, is a cross-bar 22, carrying a depending slotted post 23, the purpose of which will also appear later.

Slidably mounted upon columns 21—21, adjacent the base plate 2, by means of the 100 relatively long tubular guide bearings 24—24, is the clutch bar 25, carrying at each end a clutch element 26—26, adapted to engage the oppositely disposed upon carbons 27—27.

The use of the clutch bar 25 being common 105 to both carbons, and being provided with its long guide bearings, insures absolutely synchronous movement of the carbons, as well as absolute alignment of travel of the same.

Rigidly secured to the upper face of the 110

clutch bar 25 is the upstanding post 28 carrying an open slot at its upper end.

Also, rigidly secured to the base plate 2 of the frame is a similar post 29.

- 5 Swingly and slidably secured to the upstanding post 28 carried by the clutch bar 25, by means of the central longitudinal slot 30, is the lever 31, one end of which is swingingly connected with the upstanding slotted 10 post 29 carried by the base plate 2, and the other end is loosely connected with the depending slotted post 20 carried by the bar 10.

- Also pivoted to the depending slotted post 23 carried by the cross-bar 22, is the lever 32, carrying at one end the counter-weight 33, and having its opposite end pivoted to the upper end of the link 34, the lower end of which link is similarly connected with the lever 31 carried in the post 28.

- 20 Slidably mounted upon the corner posts 4-4 of the frame are the oppositely disposed carbon holders 35-35 to which the upper carbons 27-27 are secured by screws 36-36.

- 25 For the purpose of insulating the carbons and operating elements from the frame of the device, I use the plates or sheets 37-37 of asbestos or other suitable material. Fig. 5.

- Firmly secured to, and suspended from, the base plate 2 of the frame is the supporting rod 38, carrying at its lower end an adjustable cross-bar 39 having a relatively long tubular guide bearing 40 held in position by the screw 41, said cross-bar being provided at each end with a carbon holder 42 to which the lower carbons 43-43 are attached by screws 44-44.

- The rheostat, or resisting elements, is represented by 45, and may be provided with any ordinary shunt switch to regulate the strength of the current passing through the same.

- The operation of my device, briefly stated, is substantially as follows:

- 45 When the solenoid is energized, the armature will travel upwardly in the solenoid, carrying with it the little flat bar 17 against the pressure of the springs 16-16, but without moving the bar 10, until the compression of the springs is sufficient to overcome the 50 gravity resistance of the bar 10 and its equipment, less the gravity weight of the counter-weight 33 (which will then move downwardly), at which time the bar 10 will be lifted up. This will lift the rear end of the lever 31 which is swingingly and slidably secured to the post 28 carried by the clutch bar 25, which will also lift the clutch bar, and the clutch elements carried by this bar will engage and lift the upper carbons and establish 55 the arc.

It is obvious that in this operation the clutch bar and the carbons will travel a very materially lesser distance than the armature, causing the carbons to be more slowly and

gently separated, a result much to be desired 65 in the building up of the arc.

Also, the action of the springs 16-16 will contribute very materially to this result.

The relative movement of the various operating elements are so adjusted that when 70 the armature reaches what is known as the point of magnetic balance in the solenoid, the arc will be of proper length for service.

As the carbons burn away, however, the length of the arc gradually increases and the 75 strength of the current will correspondingly decrease until the magnetic strength of the solenoid is no longer sufficient to carry its load, at which time the armature will begin to drop, thus permitting the clutch bar 25 to 80 fall, but under the cushioning effect of the springs 16-16, and gently retarded, also, by the gravity resistance of the weight 33 (which will then move upwardly), until the clutch elements 26-26 come in contact with 85 the insulating plates or sheets 37-37, which will release the grip on the upper carbons and permit them to fall until they again come in contact with the lower carbons, thus, 90 theoretically, eliminating the arc and extinguishing the light, although the operation is so rapid that this fact is not perceptible to the eye.

As soon as the two carbons again come in contact the circuit is closed, the current again 95 flows to, and energizes, the solenoid, and this cycle of operation is repeated so long as the lights are burning.

I claim:

1. In an arc lamp, a carbon control mechanism comprising a horizontal lifting bar slidably mounted upon upright supports and carrying at each end a clutch element adapted to engage a carbon, and means for actuating said lifting bar,—said actuating means 100 including a solenoid unit, a plate also slidably mounted upon separate upright supports and controlled by said solenoid unit, and a lever having one end loosely connected with said plate, a loose connection, intermediate 105 its ends, with said lifting bar, and its other end pivoted on the opposite side of said lifting bar from said plate.

2. In an arc lamp, a carbon control mechanism comprising a horizontal lifting bar slidably mounted upon upright supports and carrying at each end a clutch element adapted to engage a carbon, and means for actuating said lifting bar,—said actuating means including a solenoid unit, a plate also slidably mounted upon separate upright supports and controlled by said solenoid unit, a lever having one end loosely connected with said plate, a loose connection, intermediate 115 its ends, with said lifting bar, and its other end pivoted on the opposite side of said lifting bar from said plate, and another lever intermediate 120 its ends above said first

mentioned lever, and carrying at one end a counter-weight, and having at its other end a loose link connection with said first mentioned lever.

- 5 3. In an arc lamp, a carbon control mechanism comprising a horizontal lifting bar slidably mounted upon upright supports and carrying at each end a clutch element adapted to engage a carbon, and means for 10 actuating said lifting bar,—said actuating means including a solenoid unit, a plate also slidably mounted upon separate upright supports and connected to the lower end of the armature of said solenoid unit, a lever having one end loosely connected with said plate, 15 having one end loosely connected with said plate, a loose connection, intermediate its ends, with said lifting bar, and its opposite end pivoted on the opposite side of said lifting bar from said plate.
- 15 4. In an arc lamp, a carbon control mechanism comprising a horizontal lifting bar

slidably mounted upon upright supports and carrying at each end a clutch element adapted to engage a carbon, and means for actuating said lifting bar,—said actuating means including a solenoid unit, a plate also slidably mounted upon separate upright supports and connected to the lower end of the armature of said solenoid unit, a lever having one end loosely connected with said plate, 25 a loose connection, intermediate its ends, with said lifting bar, and its opposite end pivoted on the opposite side of said lifting bar from said plate, and another lever pivoted intermediate its ends above said first mentioned 30 lever, and carrying at one end a counter-weight, and having at its other end a loose link connection with said first mentioned lever.

In witness whereof, I have hereunto affixed 40
my signature.

LESTER S. KUBIAC.
